(57) **CLAIM**

The ornamental design for a bed leg and glide, as shown and described.

DESCRIPTION

FIG. 1 is a perspective view of a bed leg and glide, showing our new design;

FIG. 2 is a front perspective view thereof;

FIG. 3 is a rear perspective view thereof;

FIG. 4 is a left side view thereof;

FIG. 5 is a front side view thereof;

FIG. 6 is a rear side view thereof;

FIG. 7 is a top plan view thereof; and,

FIG. 8 is a bottom plan view thereof.

The broken lines shown represent unclaimed portions of the bed leg and glide, and form no part of the claimed design.
